Primary Examiner—Bernard Ansher*Assistant Examiner*—Prabakar Deshmukh*Attorney, Agent, or Firm*—Banner, Birch, McKie & Beckett[57] **CLAIM**

The ornamental design for a stackable dough tray, as shown and described.

DESCRIPTION

FIG. 1 is a perspective view of a stackable dough tray showing our new design;

FIG. 2 is a top plan view thereof;

FIG. 3 is a bottom plan view thereof;

FIG. 4 is a front elevation thereof; the rear elevation being a mirror image thereof;

FIG. 5 is a left side elevation thereof; the right side elevation being a mirror image thereof;

FIG. 6 is a perspective view of a second embodiment of FIG. 1;

FIG. 7 is a top plan view of FIG. 6;

FIG. 8 is a bottom plan view of FIG. 6;

FIG. 9 is a front elevation of FIG. 6; the rear elevation being a mirror image thereof; and,

FIG. 10 is a left side elevation of FIG. 6; the right side elevation being a mirror image thereof.
